[57] CLAIM

The ornamental design for a toy car, as shown and described.

DESCRIPTION

FIG. 1 is a right perspective view of a toy car showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view.

The broken line showing of the hub cap in FIGS. 1, 4 and 5 is for illustrative purposes only and forms no part of the claimed design.

FIG. 1

FIG. 3

FIG. 2

FIG. 4

FIG. 5

FIG. 6

FIG. 7
